REFRIGERATOR

Filed Dec. 19, 1928

INVENTOR
John Stewart
G. W. Baldwin
ATTORNEY

UNITED STATES PATENT OFFICE

JOHN STEWART, OF DETROIT, MICHIGAN

REFRIGERATOR

Application filed December 19, 1928. Serial No. 327,015.

This invention relates to improvements in refrigerators, and refers more particularly to refrigerators of a light portable type primarily intended for such purposes as carrying lunches and the accompanying liquid refreshments, such as milk, bottled beverages or the like.

The invention aims, among other things, to provide a cheaply constructed refrigerator having only a single wall and wherein the ice chamber is so positioned that other portions of the structure are arranged between it and the outside walls so that only the top of the ice chamber may be directly affected by the temperature outside; to provide a refrigerator having side compartments at the sides of the ice chamber, a common floor for said compartments and said chamber, and openings in partitions between the chamber and the compartments contiguous to the said floor so that water from melted ice may flow into the compartments, and also higher openings through the partitions so that cold air from the ice chamber may enter the said compartments when the ice water lies above the level of the tops of the first named openings; to provide removable containers in said compartments so that food may be stored therein and protected from ice water, said containers being so constructed that even when water lies to a considerable depth cold air from the ice chamber may be admitted into the compartments below the level of the tops of the containers and allowed to reach the contents of the latter; to provide a removable top having smaller removable covers therein arranged over the compartments so that the contents of the latter may be reached without exposing the ice chamber directly to the outer air; and to provide a lower food cupboard under the ice chamber and under the said compartments.

With these and other objects and advantages in view which will become apparent as the specification proceeds, the invention, which consists in certain novel construction and combination of parts, is hereinafter more fully described with the aid of the accompanying drawings, in which:

Figure 1 illustrates a perspective view of the invention.

Figure 2 is an enlarged cross sectional view.

Figures 3 and 4 are sections on the lines 55 3—3 and 4—4 of Figure 2.

Figure 5 is a plan view and

Figure 6 a side elevation of the container.

Referring to the drawings, 1 designates a box having an open top 2 which is usually outwardly flanged to receive the margins 3 of a cover 4, and 5 denotes a downward annular projection on the said cover which fits within the upper edges of the box. Around the top 2 of the box is a resilient washer 6 against which the margins 3 of the cover form a substantially airtight joint. 7 denotes openings in the cover 4 the margins of which are preferably downturned to receive correspondingly downturned portions 8 of lids 9.

The box has a floor 10 therein which extends across its whole length and width some distance above its base 1^a. Upwardly from the floor 10 to the top of the box partitions 11 are arranged towards either side; the central portion between the partitions forms an ice chamber 12. The side portions are usually subdivided into compartments 15 preferably substantially square in cross section by other partitions 13. Through the partitions 11 lower apertures 14 extend upwardly from the floor 10 to provide means for water from melting ice in the ice chamber 12 to enter the compartments 15, and above the aperture 14 other openings 16 are provided through the partitions 11 to allow cold air from the ice chamber to enter the said compartments since water may lie in them and in the ice chamber above the level of the said aperture 14. The compartments are intended both for the storage of bottles as indicated at 17 and also for the storage of foods which would be damaged by direct contact with ice water. It will also be noted that the compartments are preferably so shaped that they will hold bottles in a substantially vertical position. The containers 18 have upper portions 18^a of such cross section that they fit snugly into the compart- 100

ments, and lower portions 18^b of reduced size so that both ice water and cold air from the ice chamber may circulate freely around them. 18^c denotes holes through the outwardly flanged intermediate portions 18^d of the containers to permit cold air from below to circulate freely in the remaining portions of the compartments.

On one side of the box 1, between its base 10 1^a and the floor 10, a cupboard 19 is provided to afford storage facilities for food. In the front of the cupboard and usually hinged as at 20^a to the lower portion of the box is a door 20, the margins of which are 15 normally held closed against the sides of the door opening 21 as by a fastener 22. Any conventional type of handles 23 may be attached to the side of the box, and 24 is a valve located substantially on the level of 20 the floor to permit water lying thereon being discharged.

While in the foregoing the preferred embodiment of the invention have been described and shown it is understood that this 25 construction is susceptible to such alterations and modifications as fall within the scope of the appended claims.

What I claim as my invention and desire to secure by Letters Patent is:

30 1. In a refrigerator, the combination of a casing open at its upper end, a removable cover thereon, a floor extending completely across said casing intermediately of its height, substantially parallel partitions in 35 said casing extending from said floor to its upper end, an ice chamber formed between said partitions, side storage compartments formed between said partitions and the sides of said casing, said partitions having apertures therethrough which extend upwards 40 from said floor through which water from melting ice in the ice chamber is adapted to flow into said compartments, and means for releasing ice water from said floor when 45 desired.

2. In a refrigerator, the combination as described in claim 1, wherein other partitions arranged substantially at right angles to the first named partitions subdivide the 50 compartments, and removable containers in said subdivided compartments having upper portions which fit snugly therein, lower portions smaller than said subdivided compartments around which ice water and cold air 55 are adapted to circulate, intermediate flanged portions joining said upper and lower portions having holes therethrough so that cold air which enters said compartments through the partition apertures may pass up 60 into the whole of the compartments.

3. In a refrigerator, the combination of a casing open at its upper end, a removable cover thereon, a floor extending completely across said casing intermediately of its 65 height, substantially parallel partitions in

said casing extending from said floor to its upper end, an ice chamber formed between said partitions, side storage compartments formed between said partitions and the sides of said casing, said partitions having apertures therethrough extending upwards from said floor and openings therethrough above the tops of said apertures, said apertures being adapted to permit water from melted ice to enter said compartments and keep 70 said compartments cool, and said openings are adapted to permit cold air from the ice chamber to enter said compartments when water from melted ice lies on the floor above the level of the tops of said apertures, means 75 for releasing water from the floor when desired, and a cupboard formed in the lower portion of the casing the top of which is formed by the underside of said floor so that cold from the ice chamber may influence the 80 temperature in said cupboard through said floor.

4. In a refrigerator, the combination of a casing open at its upper end and having an intermediate floor therein, substantially parallel partitions across said casing from the floor to the top, a removable cover on said casing, downturned flanges around said cover adapted to engage the inner margins of said casing top, said cover having openings therethrough at its sides, an ice chamber formed between said partitions, compartments formed between said partitions and said casing sides, lids on said cover 90 openings, means for admitting ice water from said ice chamber into said compartments, means for admitting cold air from said ice chamber into said compartments, a cupboard formed in said casing the roof of which is formed by said floor, one side of the casing having a doorway cut 95 therein, and a door adapted to close said doorway and being of greater width and height than said doorway so that it will bear 100 against the sides of the latter when in closed 105 position.

JOHN STEWART.
